UNITED STATES PATENT OFFICE.

DAVID HALL RICE, OF LOWELL, MASSACHUSETTS.

CASH-CARRYING APPARATUS.

SPECIFICATION forming part of Letters Patent No. 320,168, dated June 16, 1885.

Application filed April 30, 1885. (No model.)

To all whom it may concern:

Be it known that I, DAVID HALL RICE, of Lowell, in the county of Middlesex and State of Massachusetts, have invented a new and useful Improvement in Cash-Carrier Apparatus, of which the following is a specification.

My invention relates to cash-carrying apparatus; and it consists in certain improvements therein, substantially as hereinafter described and claimed.

In the drawings, Figure 1 is a side view of a portion of a track provided with my improvements and a carrier thereon. Fig. 2 is a view of the same without the carrier, taken from the right-hand end of Fig. 1.

My invention relates to improvements in the deflecting apparatus employed to divert the course of the carrier downward through the open trap in the track at a station where it is to be delivered, for which deflector I made application for Letters Patent upon the 3d day of April, A. D. 1885, Serial No. 161,085; and it further relates to combining the mechanism of such deflector with the trap closing and opening mechanism shown and described in the Letters Patent No. 314,263, granted to me March 24, 1885.

In my said former application I showed and described a movable deflector operated by the mechanism of the trap-section, or other suitable mechanism, to move into the path of the carrier and deflect it in a downward direction when the trap was open, and to rise out of the path of the carrier when the trap was closed to allow the carrier to pass it going to the station beyond.

One object of my present invention is to lock the movable deflector in position when down, so that it shall not be elevated by the impinging of a swiftly-moving carrier with it. This I accomplish as follows:

A is the track or way, composed of the rails $a\ a$ and two swinging sections, $a'\ a'$, forming the trap, pivoted at $a^2\ a^2$ in the usual manner. It is supported upon frames $a^3\ a^3$ held in position by longitudinal bars $a^4\ a^4$, and suspended in the usual manner. Two side guides, $a^5\ a^5$, serve as additional braces to the frames $a^3\ a^3$, and by their flat inner faces to cause the carrier to drop vertically down between them through the trap. These latter have an outer and inner vertical face united by a narrow longitudinal central rib between them.

D is the deflector. It is formed of a single piece of spring-wire, d , bent, as shown, so that its middle portion shall form the deflecting surface for the carrier to strike against over the part of the trap at which the carrier first arrives, and with its ends expanded so as to pass down on each side of the path of the carrier toward the direction the latter is going and pass through the pivoted sleeves $d'\ d'$, which turn freely upon pivots in one of the frames a^3 . The ends of the wire d pass down below the track and are united by a cross-bar, d^2 , to the center of which is attached a weight, d^3 , sufficient to overcome the opposite end of the deflector and tilt it up out of the way of the carrier passing over the closed trap. The wire d between its deflecting portion and its pivots d' is first carried along in a direction approximating to the horizontal, and then bent downward suddenly at d^4 on each side, thus forming a cam-shaped surface. At the end of the trap which the carrier enters is placed a cross-bar, e , supported at each end by the ends of the wire e^2 , which is carried upward and forward on each side of the trap, passing between the outer and inner faces (on each side of the trap) of the guide-pieces a^5 , the central connecting-rib connecting those faces being cut away at that point to let the wire e^2 pass through, and the wire being pivoted at e^4 on each side between said faces. The wire e^2 passes upward and forward outside the side bars a^4 , and its middle part is bent so as to cross the path of the carrier above said side-bars and beyond the two parts of the wire d of the deflector D in such a position as to hold the latter down into the path of the carrier and to be below the cam part of it, d^4 . This transverse part of wire e^2 is loaded with a weight, e^3 , fixed thereon, as shown, and made in the form of a cylinder for convenience. This weight e^3 is sufficient to bring the wire e^2 and the deflector D down into the position last above described.

To the opposite side of bar e from the wire e^2 is attached the rigid spline e^4 , projecting longitudinally of the track in the path of the carrier, which is supplied with a groove registering with the spline if it is to pass over without moving it and fall through the trap, and is without such registering-groove if intended to pass beyond this station. The two parts of the wire d which bear against the

weight e^3 , as shown in the drawings, pass it at such an angle to its wire arms e^2 that the weight locks the deflector firmly in the position shown, wires d and e^2 approaching a right angle to each other between their pivots and these points of contact. If, therefore, a carrier, passing over spline e^4 without moving it, strikes under the deflector as shown, the latter is so locked by this arrangement that its 10 spring-wire only yields between the point of impingement and locking-weight e^3 or its wire e^2 at that place. The carrier is, therefore, surely deflected through the trap, and the spring of the deflector, as described, aids in 15 this result and prevents noise from the blow of the carrier. When a carrier comes along which is to pass by this station, it rolls upon the spline e^4 and depresses it and the bar e , turning the wire e^2 upon its pivots e' and 20 raising the weighted end e^3 to the position shown by the dotted lines on Fig. 1. This releases the deflector, and its weight d^3 tilts it up out of the way of the carrier, allowing the latter to pass under, when the weight e^3 falls 25 upon the upper side of deflector-wire d and brings it back to the locked position and raises spline e^4 and bar e upward again.

This mechanism operates with the minimum of power, as all its parts turn upon pivots, and 30 the carrier does not lift the deflector, it opening automatically when unlocked by the carrier.

This mechanism is combined with the trap to carry out the second part of my invention, 35 as follows: On the upper side of the bar e and under the radial arms of the trap-sections a' two studs or pins project from the bar in such position that as the bar is lifted they will press under said radial arms and lift the trap-sections to the position shown, and as described in my said former patent, leaving the trap open when the deflector is locked down.

The weight e^3 is, of course, made heavy enough to lift the pivoted trap-sections a' , 45 as well as to depress the deflector.

When the spline e^4 is depressed and the bar e withdrawn downward, the trap-sections fall and close the trap for the carrier to pass over at the same time as the deflector rises out of 50 its way, as before described.

It is evident that the mechanism for moving the deflector-lock may be separated from that for closing the trap, if desired. It is also evident that a similar deflector and locking device 55 may be used with a trap which is normally closed and is opened by the carrier to pass through it, if desired.

The deflector mechanism is also capable of being used without the trap to arrest a carrier 60 upon the way.

C is the carrier, and d^6 d^6 are wire rods between which it falls and slides down to any desired point.

What I claim as new and of my invention 65 is—

1. In combination with the way and a trap

or space in it for the descent of the carrier, the movable deflector, mounted upon bearings, and a locking device adapted to lock said deflector in the path of the carrier, substantially as described. 70

2. The combination of the way, a trap or space in it for the descent of the carrier, the movable deflector, and the locking device adapted to lock said deflector in the path of the carrier, and having one portion of said device projected into the path of the carrier in position to enable the carrier to move and actuate the same, substantially as described. 75

3. The combination of the way, the pivoted deflector D , automatically moving out of the path of the carrier, and the pivoted weight e^3 , adapted when released to descend against the inclined surface of the deflector and move and 80 lock the same into the path of the carrier, substantially as described.

4. The combination of the way, the trap or space therein for the descent of the carrier, the pivoted deflector D and its pivoted locking-arm e^2 , provided with the spline e^4 projecting into the path of the carrier, substantially as described. 90

5. The combination of the way having the space therein for the descent of the carrier, 95 the pivoted deflector D , the pivoted arm e^2 , carrying the bar e and spline e^4 on the opposite side of its pivot, and the pivoted trap-sections a' , substantially as described.

6. The combination of the way having the space therein for the descent of the carrier, 100 the pivoted trap-sections a' , and the pivoted arm e^2 , carrying upon one end of it the part e^3 into and out of the path of the carrier and upon the other end the bar e and spline e^4 projecting into the path of the carrier, substantially as described. 105

7. In combination with the way, the trap adapted to be closed to pass the carrier over the same, and the deflector D , formed with a 110 deflecting portion swinging above the path of the carrier and supported upon the pivoted bifurcated arm d passing down upon each side of that path, and counter-weighted, substantially as described. 115

8. The combination of the way formed of rails a a , the trap-sections a' a' swinging upon pivots parallel to said way, and the side guides a^5 a^5 , extending above and parallel to said track-sections on their inside guiding-faces, 120 substantially as described.

9. The combination of the way having the trap or space in the same and the deflector D , secured in the path of the carriers and formed of spring metal or material, in its projecting and deflecting portion impinged upon by the carrier, substantially as described. 125
